CLAIM

The ornamental design for a biosensing garment, as shown and described.

DESCRIPTION

FIG. 1 is a perspective view of a first embodiment of a biosensing garment;

FIG. 2 is a front view of the first embodiment thereof;

FIG. 3 is a back view of the first embodiment thereof;

FIG. 4 is a right side view of the first embodiment thereof; and

FIG. 5 is a left side view of the first embodiment thereof.

FIG. 6 is a perspective view of a second embodiment of a biosensing garment;

FIG. 7 is a front view of the second embodiment thereof;

FIG. 8 is a back view of the second embodiment thereof;

FIG. 9 is a right side view of the second embodiment thereof; and,

FIG. 10 is a left side view of the second embodiment thereof. The broken lines immediately adjacent the shaded areas represent the bounds of the claimed design while all other broken lines are directed to environment and are for illustrative purposes only; the broken lines form no part of the claimed design.

1 Claim, 10 Drawing Sheets
